CLAIM

The ornamental design for a propeller band for dry fly, as shown.

DESCRIPTION

FIG. 1 is a perspective view of a propeller band for dry fly showing my new design in use;

FIG. 2 is a top view thereof;

FIG. 3 is a left side elevation thereof, the right side being a mirror image;

FIG. 4 is a front elevation thereof;

FIG. 5 is a rear elevation thereof; and,

FIG. 6 is a bottom view thereof.

The dry fly shown in broken lines in FIGS. 1 and 6 denotes the nature and environmental use of the design and is not part of the design.
